UNITED STATES PATENT OFFICE.

LOUIS H. VORIES, OF NEW YORK, N. Y.

GOLF-CLUB.

1,219,417.

Specification of Letters Patent. Patented Mar. 13, 1917.

Application filed April 5, 1916. Serial No. 89,005.

To all whom it may concern:

Be it known that I, LOUIS H. VORIES, a citizen of the United States, residing at the city of New York, borough of Manhattan, in the county and State of New York, have invented certain new and useful Improvements in Golf-Clubs, of which the following is a full, clear, and exact specification.

My invention relates to improvements in that type of golf clubs in which the head is both adjustable and reversible so as to permit of said head being adjusted to different angles relative to the shaft in order to adapt the club for use in making different kinds of strokes, and also to adapt said club for use by left-handed as well as by right-handed players.

Further, said invention has for its object to provide a golf club comprising a revolvable head, and a shaft to receive said head which will automatically allow for wear of the interengaging parts and insure of the same being capable of rigid securing after long, continued or repeated adjustment and use.

Further, said invention has for its object to provide a golf club in which the movable or adjustable head is constructed to receive its supporting shaft and fully conceal the interengaging parts and to protect the same against the entrance of foreign matter.

Further, said invention has for its object to provide a golf club in which the securing means is positive in its action, and which may be quickly and easily actuated without the use of tools, when changes in the position of the head relative to the shaft are to be made.

Further, said invention has for its object to provide a golf club comprising a movable head and a shaft therefor in which the adjusting and securing means are so constructed and arranged that the several parts are wholly contained within the head, and only the final or actual securing member which extends slightly beyond the head at the free end thereof be exposed to view.

Other objects will in part be obvious and in part be pointed out hereinafter.

To the attainment of the aforesaid objects and ends my invention consists in the novel details of construction, and in the combination, connection and arrangement of parts hereinafter more fully described and then pointed out in the claims.

In the accompanying drawings forming part of this specification, wherein like numerals of reference indicate like parts,—

Figure 1 is a side view showing one form of golf club constructed according to and embodying my said invention;

Fig. 2 is a side view partly in section showing the means for securing the head to its shaft and shank; the said parts being shown with the head in its normal or adjusted position;

Fig. 3 is a view similar to Fig. 2 showing the securing means released and the head shifted longitudinally upon the shaft to permit of the adjustment of the head relative to the shaft.

Fig. 4 is an enlarged detail sectional view of the adjusting means, and

Figs. 5 and 6 are end views showing the head adjusted in opposite positions for use by right and by left-handed players.

In said drawings 10 designates a tapered hollow shank adapted to receive the lower end of a shaft made of wood or other suitable material, and 11 denotes a head adjustably secured to said shank 10. The shank 10 is provided at its lower end with a shoulder 12 from which extends a solid shaft 13 formed integrally with the shank 10. The shaft 13 is provided at its secured end with a gear or conical member 14 which tapers slightly from the secured to the free end of said shaft 13, and is provided with a series of longitudinal radial projections 14a. The conical member 14 is separated from the shoulder 12 of the shank 10 so as to provide a space 15 between the rear side of said conical member and the face of the shoulder 12. The outer or free end of the shaft 13 is reduced in diameter and provided upon its outer surface with screw-threads 16, and within said reduced outer end with a longitudinal threaded aperture.

The head 11 is provided with a central longitudinal opening 17 which extends entirely through said head 11 from end to end, and has a projecting flange or rim 18 at its inner or rear edge which forms a socket 19 upon the inner end of said head of such diameter that the same will readily receive and inclose the shoulder portion 12 at the lower end of the shank 10. The head 11 is further provided at its inner end and directly adjoining the socket 19 with a series of longitudinal recesses 20 which are adapt-

ed to interengage with the projections 14* of the conical member 14 fixed upon the shaft 13.

Within the outer end of the head 11 is disposed a longitudinal-movable locking sleeve 21 having a knurled head 22 at its outer end and provided at its inner end, which is disposed within the longitudinal opening 17 in the head 11, with internal screw-threads 23 which are adapted to engage with the screw-threads 16 upon the outer reduced end of the shaft 13 when the head 11 is properly and fully adjusted in position upon the shaft 13.

The sleeve 21 is maintained within the head 11 and in operative relation with respect to the outer end of the shaft 13 by means of a screw 24 whose head is disposed within the sleeve 21, and whose threaded portion extends through the opening at the inner end thereof, and fixedly engages the internal screw-threads provided within the reduced end of the shaft 13. The arrangement of the screw 24, with relation to the outer end of the reduced end of the shaft, is such that when the under side of the head 24 engages with the shoulder formed at the inner end of the sleeve 21, the head 11 may be drawn outwardly upon its shaft 13 to such an extent as will cause the longitudinal recesses 20 at the inner end thereof to be disengaged from the longitudinal projections 14* on the conical member 14 of the shaft 13, and permit of the head 11 being adjusted to any desired position upon its shaft. When the proper adjustment has been effected and the head fully returned to its normal position with the recesses 20 thereof in engagement with the projections on the conical member 14 on the shaft 13, the head of the screw 24 will come about flush with the outer edge of the head 11, and thus permit of the sleeve 21 being rotated and the screw-threads at the inner end thereof to become engaged with the screw-threads 16 provided upon the reduced end of the shaft 13. By rotating the sleeve 21 by means of the knurled head 22 thereon, the head 11 may thereupon be firmly secured in position upon its shaft and be held against movement both rotary and longitudinally thereon.

The operation of my improved club is for the most part obvious. Attention, however, is directed to the fact that when it is desired to make a change in the angle or position of the head relative to the shaft, it merely becomes necessary to unscrew the locking sleeve 21 from its engagement with the outer threaded end of the shaft 13, and then draw said sleeve 21 outwardly until the inner end thereof engages with the under side of the head of the screw 24 when the further movement of said sleeve will be arrested. Hereupon, the head 11 is drawn outwardly upon the shaft, as far as it will go, when the lon-

gitudinal recesses 20 at the inner end thereof will have become disengaged from the longitudinal projections 14* on the conical member 14, and thus permit of the head 11 being adjusted to any desired position. When the desired adjustment has been effected, the head 11 is again forced inwardly as far as it will go, and the locking sleeve 21 again screwed home upon the reduced end of the shaft 13, whereby the head 11 will be rigidly secured in its adjusted position.

It will be noted that by reason of the novel construction of the inner end of the head 11 and the co-operating shoulder 12 and conical member 14 on the shaft 13, a rigid fit will be insured at said point, and that such fit will be insured without regard to the number of times that the head 11 has been adjusted upon its shaft owing to the fact that the conical member 14 has a slight taper which will serve to take up wear as the same occurs. By reason of the flange 18 at the inner end of the head 11 receiving and snugly inclosing the shoulder portion 12 at the lower end of the shank 10, all possibility of foreign matter or fluid entering said head will be prevented, and all possibility of the parts becoming rusted or otherwise unduly secured together wholly precluded.

Further it is to be noted that if the head 11 is adjusted to the position A, as indicated by broken lines at Fig. 5, the club may be used in making a stymie shot, and that as the head is three-faced, and all of said faces provided with longitudinal grooves 11*, each face has its uses depending upon the choice of the player.

Having thus described my said invention, what I claim and desire to secure by Letters Patent is:—

1. A golf club comprising a shank, a shaft extending therefrom, a head adjustably mounted upon said shaft, holding means arranged partly upon said shaft and partly upon said head, a securing member longitudinally-movable with reference to said shaft adapted to engage with the end thereof and with the end of said head for securing said head to its adjusted position upon said shaft, and means for limiting the outward movement of said member, substantially as specified.

2. A golf club comprising a shank, a shaft extending therefrom, a member secured to said shaft adjacent to its fixed end, a head mounted upon said shaft, means upon said head adapted to engage with the member upon said shaft for holding said head to its adjusted position upon said shaft, a longitudinally-movable securing member disposed within said head upon the free end of said shaft and adapted for engagement with the end thereof and with the outer end of said head, whereby to secure said head to its

adjusted position upon said shaft, and means for limiting the outward movement of said securing member, substantially as specified.

3. A golf club comprising a shank, a shaft 5 extending therefrom, a longitudinally-ribbed member secured to said shaft adjacent to its fixed end, a head mounted upon said shaft, means upon said head registering with the longitudinally-ribbed member upon said 10 shaft and adapted to engage therewith for holding said head to its adjusted position upon said shaft, a securing member disposed within said head and longitudinally-movable with reference to said shaft and adapted 15 to engage the free end of said shaft and the outer end of said head, whereby to hold said head to its adjusted position upon said shaft, and means for limiting the outward movement of said securing member, substantially as specified.

4. A golf club comprising a shank, a shaft extending therefrom, a head mounted upon said shaft, holding means arranged partly upon said shaft and partly upon said head 25 for holding said head to its adjusted position upon said shaft, said head being longitudinally movable with respect to said shaft whereby it may be moved outwardly with respect thereto to render said holding means 30 inoperative, longitudinally-movable means operatively associated with said shaft and said head and serving when in its innermost position to hold said head against movement relatively to said shaft, and when 35 in its outermost position to limit the outward movement of said head with respect to said shaft, and means for limiting the outward movement of said longitudinally-movable means, substantially as specified.

5. A golf club comprising a shank, a shaft 40 extending therefrom, a shoulder upon the end of said shank, a tapering member secured to said shaft adjacent to said shoulder but separated therefrom, radial projections 45 upon said member, a head mounted upon said shaft, recesses upon the inner end of said head adapted to engage with the radial projections on said tapering member for holding said head to its adjusted position 50 upon said shaft; said shaft having its outer end reduced and screw-threaded, and a sleeve member longitudinally-movable within said head and secured to the end of said shaft and adapted to engage with the end of 55 said shaft and with the end of said head, whereby to secure said head to its adjusted position upon said shaft, substantially as specified.

6. A golf club comprising a shank, a shaft 60 extending therefrom, a head mounted upon said shaft, holding means arranged partly

upon said shaft and partly upon said head for holding said head to its adjusted position upon said shaft, a longitudinally-movable member engaging the free end of said 65 shaft and adapted when in its innermost position to engage said head to hold it against longitudinal movement relatively to said shaft, said head being free to move longitudinally of said shaft when said member 70 is in its outermost position, and means to limit the outward movement of said member, substantially as specified.

7. A golf club comprising a shank, a shaft 75 extending therefrom, a head mounted upon said shaft, holding means arranged partly upon said shaft and partly upon said head for holding said head to its adjusted position upon said shaft, a longitudinally-movable member engaging the free end of said 80 shaft and adapted when in its innermost position to engage said head to hold it against longitudinal movement relatively to said shaft, said head being free to move longitudinally of said shaft when said member is in 85 its outermost position, and means secured to the free end of said shaft to limit the outward movement of said member, substantially as specified.

8. A golf club comprising a shank, a shaft 90 extending therefrom, a shoulder upon the end of said shank, a conical member fixed upon said shaft adjacent to its fixed end but separated from said shoulder, a series of longitudinal radial projections on said conical 95 member, a head loosely disposed upon said shaft provided at its inner end with a socket adapted to inclose the shoulder upon the lower end of said shank, said head being provided at its inner end with a plurality of longitudinal 100 recesses adapted to engage with the longitudinal radial projections on said conical member; the outer end of said shaft being reduced in diameter and having said reduced portion exteriorly and interiorly 105 screw-threaded, a sleeve member longitudinally-movable within said head upon the reduced end of said shaft and provided with a screw-threaded portion adapted to engage with the reduced exteriorly threaded portion 110 of said shaft, and a locking screw disposed within said sleeve member and secured within the interiorly threaded reduced portion of said shaft, substantially as specified.

Signed at the city of New York, in the 115 county and State of New York, this 16th day of March, one thousand nine hundred and sixteen.
